UNITED STATES PATENT OFFICE

FRANK W. WILKINSON AND FERDINAND ZIGANEK, OF WEST TOLEDO, OHIO.

DOOR-LOCK.

1,107,736.

Specification of Letters Patent. Patented Aug. 18, 1914.

Application filed April 18, 1914. Serial No. 832,820.

To all whom it may concern:

Be it known that we, FRANK W. WILKINSON and FERDINAND ZIGANEK, citizens of the United States, residing at West Toledo, in the county of Lucas and State of Ohio, have invented certain new and useful Improvements in Door-Locks, of which the following is a specification, reference being had to the accompanying drawings.

10 This invention relates to improvements in door locks, and particularly to locks which are adapted for application to automobile doors or the like.

15 An object of this invention is the provision of a lock of this character by means of which the door may be easily closed without the necessity of slamming the door to engage the latch bar in its keeper.

20 Another object of this invention is the provision of a lock of this character which is provided with a spring pressed latch bar, the lock including automatic means for holding the latch bar in inoperative position against the tension of its spring, when the 25 door is open, and also automatic releasing mechanism for releasing the latch bar when the door has been moved to its closed position.

25 A still further object of this invention is the provision of a lock comprising a casing, in which a slidable spring pressed latch bar is mounted, the spring normally forcing the latch bar to its outermost position, the casing carrying a hook which is adapted 30 for engagement in a notch in the latch bar when the same is moved to its innermost position to hold the latch bar in inoperative position against the tension of its spring, the casing also carrying a releasing member 35 which normally projects from the casing so that upon closing of the door, the releasing member is engaged against the latch plate on the door frame and moved inwardly to release the hook from engagement with the latch bar whereupon the same will be moved outwardly by its spring into engagement with the keeper opening in the latch plate.

40 With these and other objects in view, our invention consists in the novel construction, combination, and arrangement of parts to be hereinafter more fully described, claimed, and illustrated in the accompanying drawing, in which,

45 Figure 1 is a vertical sectional view of our improved lock. Fig. 2 is a sectional

view substantially on the line 2—2 of Fig. 1. Fig. 3 is a sectional view on the line 3—3 of Fig. 1. Fig. 4 is a sectional view on the line 4—4 of Fig. 1.

50 Referring more particularly to the drawing, the numeral 1 designates a casing which is adapted to be positioned in the door 2 of an automobile or the like so that the front wall of the casing is disposed flush with the forward edge of the door. Slidably disposed through an opening 3 in the front wall of the casing is a latch bar 4, the latch bar 4 having a rearwardly extending reduced arm 5 which projects through a relatively 55 smaller opening 6 in the rear wall of the casing. Disposed around the rearwardly extending arm 5 of the latch, is a helical spring 7, one end of the spring bearing against the rear wall of the casing and the forward end of the spring bearing 60 against the rear end of the latch to normally force the same outwardly so that the forward end of the latch projects through the opening 3 in the front wall of the casing. 65

70 Pivotedly mounted upon a pin 8 which is secured at its opposite ends in the side walls of the casing above the upper edge of the latch bar 4 and adjacent the rear end of the casing, is a bell crank lever 9, one 75 arm 10 of which extends forwardly of the casing in a substantially horizontal position, and the free end thereof being hooked as at 11, the hooked end of the arm normally engaging the upper edge of the latch 4. The 80 other arm 12 of the lever 9 extends upwardly within the casing adjacent the rear end thereof for a purpose to be hereinafter more fully described. The outer side wall 85 of the casing is provided with a horizontally disposed elongated slot 13 through which a laterally extending pin 14 is disposed, and the outer end of the pin carrying a knob 15 by means of which the latch bar may be moved inwardly of the casing. A notch 16 90 is formed in the upper edge of the latch bar intermediate of its ends, so that upon inward movement of the latch bar, the hooked end 11 of the lever 9 moves downwardly 95 into the notch 16 to hold the latch in its innermost position against the tension of its spring 7.

100 Projecting through an opening 17 in the front wall of the casing above the opening 3, is one end of an automatic latch releasing 110 member, the releasing member comprising a bearing shaft which is formed of two com-

plemental sections 18, each of the sections being enlarged at one end as at 19, and being formed forwardly of the enlarged portion 19 with a reduced substantially semi-circular extension 20, the reduced portion of each member forming a shoulder 21 at its junction with the enlarged portion 19 thereof. When the sections 18 of the member are placed against each other, the curved portions 20 form a journal for the reduced intermediate portion 22 of a roller 23; and to hold the sections 18 of the bearing member in engagement with the roller, a helical spring 24 is mounted upon the inner ends of the sections, the spring extending normally from the enlarged portions 19 of the members to their inner ends. To slidably support the inner end of the bearing member, an angular bracket 25 is provided, one end of the bracket extending below the bearing member in parallel relation therewith, and having an apertured extremity 26, the apertured extremity 26 communicating with an opening in the front wall of the casing, for the reception of a screw 27 upon which a nut 28 is disposed, so that upon turning of the screw in the proper direction, the nut 28 is moved forwardly upon the screw against the inner face of the down-turned extremity 26 to hold the same against the front wall of the casing. The other end of the angular bracket 25 extends vertically within the casing, and is provided with an opening therein, the upper extremity of the vertical arm 35 of the bracket being slidably disposed in a slot 29 in the upper wall of the casing. It will be readily seen, from the drawing, that the spring 24 bears at its forward end against the enlarged portions 19 of the sections 18 of the bearing member and at its rear end against the vertical portion of the bracket 25 to normally force the roller 23 outwardly of the casing, the outward movement of the roller being limited by the engagement of the shoulders 21 with the inwardly extending lugs 30 formed on the opposite side walls of the opening 17 in the front wall of the casing. To normally force the hooked arm of the bell crank lever 9 downwardly against the upper edge of the latch 4, a spring 31 is provided, the upper end of the spring being suitably connected to the horizontal arm of the angular bracket 25, the lower end of the spring engaging around an upstanding stem 33 on the horizontal arm of the bell crank lever adjacent its outer end.

In the practical use of my device, with the door in closed position, the latch 4 will be extended within its keeper, and the roller 23 will be maintained within the casing by reason of its engagement with the latch plate on the door frame; and to open the door, the knob is grasped and moved inwardly to release the latch from engagement with its keeper. Upon movement of the outer end of the door with the roller 23 in its inner position, it will be seen that the inner ends of the sections 18 of the bearing member engage the upper extremity of the vertically extending arm 12 of the bell crank lever, thereby holding the hooked end of the bell crank lever upwardly against the tension of its spring 31, and upon pulling the other end of the door outwardly by the knob 14, the roller 23 will be forced to its outermost position, thereby allowing the spring 31 to force the horizontal arm of the bell crank lever downwardly to engage the hooked end 11 thereof in the notch 16 in the latch to hold the same in its inner position against the tension of its spring 7. When the door is again closed, the roller 23 engages the latch plate on the door frame, and is moved inwardly thereby so that the inner ends of the sections 18 engage the upper extremity of the vertical arm 12 of the bell crank lever moving the same inwardly and moving the horizontal arm thereof upwardly so as to remove the hooked portion 11 out of engagement with the notch 16, thereby allowing the latch 4 to move into engagement with its keeper by reason of the expansion of the spring 7.

From the above description, taken in connection with the accompanying drawing, it will be seen that we have provided a door lock by means of which the door may be easily and quickly closed without the necessity of slamming the same to force the latch inwardly of the casing when the same engages the latch plate, as the latch in our improved device is normally maintained within its casing when the door is in open position.

Having thus fully described our invention, what we desire to secure and claim by Letters Patent, is:

1. A door lock comprising a casing, a spring pressed latch slidably mounted in the casing, automatic means for holding the latch in inoperative position against the tension of its spring, automatic releasing mechanism slidably mounted in the casing, said releasing mechanism consisting of a shaft comprising two sections, each of the sections being provided with a semi-circular extension, a roller having a reduced intermediate portion engaged between the semi-circular extensions of the sections of the shaft, means for holding said sections of the shaft together to secure the roller therebetween, and means for normally forcing said shaft outwardly of the casing, the inner end of said shaft being disposed in alignment for holding the latch in inoperative position, whereby upon inward movement of the roller the latch is released.
2. A door lock comprising a casing, a spring pressed latch slidably mounted in the casing, automatic means for holding the

latch in inoperative position against the tension of its spring, a bracket mounted in the casing, automatic releasing mechanism slidably mounted in the casing, said releasing mechanism including a roller having a reduced portion intermediate of its ends, a shaft comprising two sections each of which having a substantially semi-circular extension for engagement around the reduced portion of the roller, said sections being formed with shoulders inwardly of the semi-circular extensions, a spring mounted on the sections to hold the same together, the inner end of the sections being slidably disposed through the bracket, the spring bearing at one end against the bracket and at its other end against said shoulders to normally force the roller outwardly of the casing, the inner end of the shaft being disposed in alignment with the means for holding the latch in inoperative position whereby upon inward movement of the roller the latch is released.

3. A door lock comprising a casing, a spring pressed latch slidably mounted in the casing, automatic means for holding the latch in inoperative position against the ten-

sion of its spring, an angular bracket slidably mounted in the casing, automatic releasing mechanism slidably mounted in the casing, said releasing mechanism consisting of a roller having an inwardly extending shaft connected thereto, the inner end of said shaft being slidably disposed through one end of said bracket, a spring mounted on said shaft for engagement against the inner end of the bracket to normally force the roller outwardly of the casing, means for adjusting said bracket to regulate the tension of said spring, the inner end of said shaft being disposed in alignment with the means for holding the latch in inoperative position, whereby upon inward movement of the roller the latch is released.

In testimony whereof we hereunto affix our signatures in the presence of two witnesses:

FRANK W. WILKINSON.
FERDINAND ZIGANEK.
